UNITED STATES PATENT OFFICE.

CLEVELAND WILHITE, OF ST. LOUIS, MISSOURI, ASSIGNOR TO AMERICAN MANUFACTURING COMPANY, OF ST. LOUIS, MISSOURI, A CORPORATION OF MASSACHUSETTS.

CUTTING DEVICE.

Application filed September 8, 1924. Serial No. 736,460.

This invention relates generally to cutting devices, and particularly to a simple and inexpensive cutting device which may be used to sever the strands which make up a hank of hemp. In most cases prior to this invention hanks of hemp were severed by moving them along the cutting edge of a stationary knife while exerting a downward pull on said hank of hemp. This method was found to be slow and laborious, and I have therefore devised the apparatus disclosed in the present application, which, briefly stated, comprises a reciprocatory knife with which is associated means whereby the hemp is presented to the cutting edge of the knife in a manner to very effectively sever said hemp.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprises changes, variations and modifications which come within the scope of the claims hereunto appended.

Fig. I is a plan view of my improved cutting device.

Fig. II is a side elevation of the cutting device shown in Fig. I.

Fig. III is a view partly in elevation and partly in longitudinal vertical section of my cutting device.

Fig. IV is a section on line IV-IV of Fig. III.

Fig. V is a section on line V-V of Fig. III.

Fig. VI is a section on line VI-VI of Fig. III.

Fig. VII is an end elevation of the cutting device with portions thereof broken away.

In the drawings, A designates my improved cutting device which comprises a bracket B by which the cutting mechanism of said cutting device is supported, said bracket preferably being secured to a wall or other stationary element so that the cutting mechanism will be located at approximately the same elevation as the shoulders of the operator. Secured to the upper face of the bracket B is a pair of spaced apart supporting bearings 1 by which is supported an elongated tube 2, said tube being provided with a slot 3 which is located at the upper

side of said tube and extends from end to end thereof. The supporting bearings 1 are fixed to the stationary bracket B and the tube 2 is secured within said bearings in any convenient manner so that said tube is maintained in a fixed position.

Arranged within the stationary tube 2 is a bar 4, said bar being or approximately the same diameter as the inside of the tube 2 and being capable of reciprocating therein. The bar 4 is provided with an elongated recess 5 which is of approximately the same width as the slot 3 in the stationary tube 2, and said recess 5 registers with said slot 3 as shown in Figs. IV and VI. 6 designates a blade-retaining member which comprises a bifurcated portion 7 and a lower, relatively thin portion 8. The blade-retaining member 6 is of approximately the same length as the recess 5 in the reciprocating bar 4, and the lower portion 8 of said blade-retaining member extends into said recess, as shown in Figs. III, IV and VI. To fix the blade-retaining member 6 to the reciprocating bar 4 I employ pins 9, which pass through said bar 4 and through the lower portion 8 of the blade-retaining member 6. Supported by the bifurcated portion 7 of the blade-retaining member 6 is a cutting blade 10, said cutting blade being secured to said blade-retaining member by means of pins 11 which pass transversely through the spaced apart legs of the bifurcated portion 7 of the blade-retaining member and through the lower portion of the blade 10.

It is apparent from the foregoing that the bar 4, blade-retaining member 6 and cutting blade 10 are secured together to produce a single unit, and it is also plain that if the bar 4 were reciprocated said blade-retaining member and said cutting blade would be reciprocated with it.

12 designates a shaft which is supported in suitable bearings mounted on the bracket B, said shaft 12 being caused to rotate by any suitable means. Mounted on the shaft 12 and rigidly fixed thereto at an end thereof is a disk 13, said disk having associated with it a connecting arm 14, one end of which is pivotally connected to said disk by means of a stud bolt 15 and the other end of which is connected to the bifurcated end portion 4' of the bar 4 by means of a pin 16. The bifurcated end portion 4' of the bar 4 is in the form of a crosshead, and said crosshead is

arranged in a guideway 17, as shown clearly in Figs. II and III, in such manner that it will reciprocate therein.

From the foregoing it is plain that when the disk 13 is rotated reciprocatory motion will be imparted to the bar 4 through the operation of the connecting arm 14, and as the cutting blade 10 is rigidly fixed to said bar 4, said blade will also be reciprocated.

10 Mounted on the stationary tube 2 is a member 18 which forms a part of the means by which the hemp to be cut is presented to the reciprocating knife. The member 18 comprises a split cylindrical lower portion 19 which is adapted to encircle the stationary tube 2, the legs 20 of said split cylindrical portion being drawn together by clamping bolts 21 whereby said split cylindrical portion is caused to grip said tube 2 to maintain the member 18 in a fixed position thereon. The member 18 also includes a wall 22 provided with a comparatively wide inclined portion 23 and a vertical portion 24, said wall 22 being provided with the required 25 rigidity by a web 25 (Figs. II and III). Secured to the member 18 is a bowed sheet of material 26 which is of approximately the same width as the wall 22 of the member 18, and a portion of said bowed sheet 30 of material is arranged in alignment with the face of the inclined portion 23 of the wall 22. The bowed sheet 26 extends upwardly and rearwardly from the member 18 and its function is to aid in guiding the hemp to its proper position to be severed.

Arranged on the stationary tube 2 is a second member 27 which cooperates with the member 18 in a manner to produce a feeding device adapted to cause the hemp 40 to be properly presented to the reciprocatory knife. The member 27 is very similar in construction to the member 18, said member 27 having a split lower portion 28 which surrounds the stationary tube 2, a comparatively wide wall 29 having an inclined portion 30 and a straight portion 31, and a strengthening web 32 to give said wall 29 the required rigidity. As already stated, the member 18 is arranged in a fixed position on the stationary tube 2, but this is not true of the member 27, the clamping screws 33 associated with the split lower portion 28 of said member not being tightened to the extent that said member would be rigidly fixed to the tube 2 but said member being capable of moving longitudinally of said tube 2. To prevent the member 27 from rotating relative to the tube 2 I employ a key 34 (Figs. IV and VI) which is arranged in keyways 45 in the tube 2 and in the member 27. Secured to the member 18 is a guard 35 which extends over the path of travel of the cutting blade 10, and secured to the member 27 is a similar guard 36 which extends over the cutting blade at its outer end. The guards

35 and 36 are intended to prevent the person of the operator from accidentally coming into contact with the reciprocating cutting blade of the device. Extended from the member 27 to the outer end of the guard 36 is a strip of material 37 which serves the dual function of aiding in the support of said guard and acting as a guide member for the hemp, so that said hemp will be directed between the members 18 and 27.

38 designates coil springs which are arranged at opposite sides of the members 18 and 27, one end of each coil spring being attached to the fixed member 18 and the opposite end of said coil spring being attached to the movable member 27. To prevent hemp from becoming entangled in the coil springs 38 I employ guards 39 which are arranged adjacent to said coil springs, as shown in Figs. IV, V, VI and VII. 40 designates a guard member which is secured to one of the supporting bearings 1 to prevent access to the free end of the reciprocatory bar 4.

In the operation of my improved cutting device the operator arranges the hank of hemp to be severed in the approximate shape of an inverted letter U. The hank of hemp is then thrown over the cutting device in a manner to cause the curved portion thereof to be located between the inclined wall portions 23 and 30 of the members 18 and 27 and the straight portions thereof to hang downwardly at the sides of the device. The operator then grasps the downwardly hanging portions of the hank of hemp and exerts a downward pull thereon, which will cause the member 27 to be moved away from the member 18 and thus permit the hemp to be drawn between the straight portions 24 and 31 of the walls 22 and 29 of the members 18 and 27 and into contact with the reciprocating blade 10. When the hemp has been severed, the downward pull thereon causes the portions of said hemp to be drawn from the cutting device and the coil springs 38 will then return the movable member 27 to its normal position. By employing the spring-controlled movable member 27 a feeding device is provided which is self-adjusted and which will retain the hemp in the form of a compact body while it is being severed.

I claim:

1. A cutting device comprising a reciprocatory cutting element, and means whereby the material to be cut is guided to said reciprocatory cutting element, said means comprising a stationary portion and a movable portion and said movable portion being adapted to be moved by the material to be cut as said material is drawn into contact with said reciprocatory cutting element to retain said material in compact form while same is being severed.

2. A cutting device comprising a recipro-

- 5 catory cutting element, and means whereby the material to be cut is guided to said reciprocatory cutting element, said means comprising a fixed member having an inclined 50 wall and a movable member having an inclined wall arranged opposite to the inclined wall of the first mentioned member, said movable member being adapted to be moved by the material to be cut when said material 55 is being drawn into contact with said reciprocatory cutting element to retain said material in compact form while it is being severed.
- 10 3. A cutting device comprising a reciprocatory cutting element, and means whereby the material to be cut is guided to said reciprocatory cutting element, said means comprising a fixed member having an inclined wall, a movable member having an inclined 60 wall arranged opposite to the inclined wall of the first mentioned member, and means whereby said movable member is returned to its normal position after it has been moved, 65 said movable member being adapted to be moved by the material to be cut when said material is being drawn into contact with said reciprocatory cutting element to retain said material in compact form while it is being severed.
- 20 4. A cutting device comprising a reciprocatory cutting element, and means whereby the material to be cut is guided to said reciprocatory cutting element, said means comprising a fixed member having an inclined 70 wall, a movable member having an inclined wall arranged opposite to the inclined wall of the first mentioned member, and a coil 75 spring adapted to return said movable member to its normal position after it has been moved, said movable member being adapted to be moved by the material to be cut when said material is drawn between said members and to retain said material in compact 80 form while it is being severed.
- 25 5. A cutting device comprising a stationary element, a reciprocatory cutting element, and means whereby the material to be cut is guided to said reciprocatory cutting element, said means comprising a member mounted 85 on and rigidly fixed to said stationary element, and a second member movably mounted on said stationary element, said movable member being adapted to be moved by the material to be cut when said material is being drawn into contact with said reciprocatory cutting element to retain said material in compact form while it is being severed.
- 30 6. A cutting device comprising a stationary tubular member, a reciprocatory cutting element, and means whereby the material to be cut is guarded to said reciprocatory cutting element, said means comprising a member mounted on said stationary tubular member and having clamping means whereby it may be rigidly fixed thereto and a second member mounted on said stationary tubular member and adapted to move longitudinally thereof, said movable member being adapted to be moved by the material to be cut as it is drawn into the device and to retain said material in compact form while it is being severed.
- 35 7. A cutting device comprising a stationary tubular member, a reciprocatory cutting element, and a means whereby the material to be cut is guarded to said reciprocatory element, said means comprising a member mounted on said stationary tubular member and having clamping means whereby it may be rigidly fixed thereto and said member being provided with an inclined wall, a second member mounted on said stationary tubular member and adapted to move longitudinally thereof, the last mentioned member being provided with an inclined wall which is arranged opposite to the inclined wall of the first mentioned member, said movable member being adapted to be moved by the material to be cut as said material is drawn into the device and to retain said material in compact form while it is being severed, and a coil spring associated with said movable member and adapted to return same to its normal position after it has been moved.
- 40 8. In testimony that I claim the foregoing I hereunto affix my signature.
- 45

CLEVELAND WILHITE.
